[57] **CLAIM**

The ornamental design for an adaptor for motorized tools, as shown and described.

DESCRIPTION

FIG. 1 is a top plan view of the adaptor for motorized tools showing my new design;

FIG. 2 is an end elevation view thereof;

FIG. 3 is a side elevation view thereof;

FIG. 4 is an end elevation view thereof;

FIG. 5 is a bottom plan view thereof;

FIG. 6 is a side elevation view thereof;

FIG. 7 is a fragmentary perspective view of a modified right hand end form of the adaptor for motorized tools described in FIG. 1, showing my new design.

FIGS. 1, 3, 5 and 6 are broken away and show indeterminate length.
